(No Model.)

J. T. POMEROY.
PNEUMATIC MILKER.

No. 439,552.

Patented Oct. 28, 1890.

UNITED STATES PATENT OFFICE.

JULIUS T. POMEROY, OF EDGERTON, WISCONSIN.

PNEUMATIC MILKER.

SPECIFICATION forming part of Letters Patent No. 439,552, dated October 28, 1890.

Application filed January 22, 1890. Serial No. 337,727. (No model.)

To all whom it may concern:

Be it known that I, JULIUS T. POMEROY, of Edgerton, in the county of Rock and State of Wisconsin, have invented a new and Improved Pneumatic Milker, of which the following is a full, clear, and exact description.

My invention relates to improvements in milking-machines; and the object of my invention is to provide a simple and efficient device that may be easily connected with the teats and udder of a cow, that will quickly transfer the milk from the udder of the cow to the pail of the machine, and that will prevent the milk from being contaminated by foreign and offensive matter.

The invention will be hereinafter fully described, and specifically pointed out in the claims.

Reference is to be had to the accompanying drawings, forming a part of this specification, in which similar letters of reference indicate corresponding parts in all the figures.

Figure 1 is a vertical section of the machine; Fig. 2, a detail view of the end of one of the milking-tubes that is inserted in a teat; Fig. 3, a plan view of the machine with the pump-tube in section on the line *x* *x* of Fig. 1, and Fig. 4 a detail view showing the manner of attaching the top cover to the pail.

The pail A is provided with a suitable handle B, by which it may be carried about, with a spout C, through which the milk is poured, and with a removable cover D, to which is attached the air-pump tube E. The pail A is also provided with a shoulder *a* around the opening in the top upon which the cover D rests and with two upwardly and forwardly extending lugs *b*, which are attached to the top of the pail upon opposite sides of the opening in the top, and which extend above the cover D. The lugs *b* are each provided with a thumb-screw *d*, which extends downwardly through the lugs and engages the laterally-extending ears *e* of the cover D and holds the cover tightly upon the pail. The cover D is provided upon opposite sides with an ear *e*, which may be turned beneath the thumb-screws *d* of the lugs *b* when the cover is to be fastened in place, and with an annular shoulder *f*, which extends around its lower edge and fits closely upon the shoulder *a* of

the pail. When the cover is to be fastened to the pail, a packing-washer *g*, of rubber or other suitable material, is placed upon the shoulder *a* of the pail, and the cover D placed upon the pail so that the shoulder *f* will rest upon the packing-washer. The cover is then turned till the ears *e* are beneath the thumb-screws *d*, when the thumb-screws are turned down, and, impinging upon the ears, they will fasten the cover securely upon the pail, and the packing-washer *g* will insure an air-tight joint.

The tube E opens through the cover D into the pail A, at which point it is provided with an ordinary check-valve *h*, which opens from the pail into the tube. Above the valve *h*, and movable vertically in the tube E, is a piston F, which is provided with an ordinary suction-valve *i*, and which is pivoted by the cross-bar *j* to the piston-rod II, which extends upwardly through the removable cap E' at the top of the tube, and is provided with a suitable handle J, by means of which it is operated. This makes a very simple air-pump, and by grasping the handle J and moving the piston up and down in the tube E the air may be pumped from the pail. I do not confine myself to the use of this pump, however, as any suitable pump may be employed. Opening from the upper part of the pail and upon one side thereof are four projecting metal tubes *k*, upon which are fitted four rubber tubes *k'*, which are to connect the pail A with the udder of a cow. The rubber tubes *k'* are of a convenient length, are provided at the free ends with a metal nipple *l*, and are also provided with a section of glass tube *m* near the pail, which enables the operator to see if the milk is flowing properly through the tubes. The nipple *l* is provided with a spreader *l'*, which extends outwardly from the end thereof, and which consists of two fine wires having their ends attached to the tube, and having their outer extremities bent to form a dull point. The wires composing the spreader *l'* are placed at right angles to each other and are so bent that the formed spreader will have an oblong shape, and will terminate in a dull point.

The machine is operated as follows: The pail A is placed upon the floor or ground at

one side of the cow and the nipples *l* and spreaders *l'* inserted in the cow's teat. The nipples will fit closely in the vent of the teat and the spreader will extend upwardly into the milk-receptacles and hold the tissues apart so that the milk will flow through the nipples and tube to the pail. When the tubes are connected with the cow's teats the air-pump is worked, thus creating a vacuum in the pail, and the suction from the pail, combined with the action of the spreaders, will cause the milk to flow quickly and freely to the pail till the cow is milked dry. It will thus be seen that the cow will be quickly and easily milked. and as the pail is tightly covered the milk will be entirely free from contamination. When the pail is to be emptied, the thumb-screws *d* are loosened and the cover *D* removed.

Having thus described my invention, what I

claim as new, and desire to secure by Letters Patent, is—

1. In a milker, a tube *l*, provided with a spreader *l'*, consisting of two wires looped and crossed at their outer ends and secured at their inner or free ends to the tube, the wires being disconnected at their point of crossing, substantially as set forth.

2. The combination, with a milk-receptacle provided with an air-exhausting mechanism, of tubes leading from the vessel and provided at their outer ends with spreaders consisting of looped and crossed wires disconnected at their points of crossing and connected at their inner ends with the said tubes, substantially as set forth.

JULIUS T. POMEROY.
